DESIGN FOR A COMBINED NAPKIN AND MENU HOLDER AND STRAW DISPENSER

Benjamin M. Oswell, Los Angeles, Calif.

Application August 24, 1939, Serial No. 86,860

Term of patent 14 years

To all whom it may concern:

Be it known that I, Benjamin M. Oswell, a citizen of the United States, residing at Los Angeles, in the county of Los Angeles and State of California, have invented a new, original, and ornamental Design for a Combined Napkin and Menu Holder and Straw Dispenser, of which the following is a specification, reference being had to the accompanying drawing, forming part thereof.

Fig. 1 is a front elevational view of a combined napkin and menu holder and straw dispenser, showing my new design.

Fig. 2 is a rear elevational view of the combined napkin and menu holder and straw dispenser.

Fig. 3 is a top plan view.

I claim:

The ornamental design for a combined napkin and menu holder and straw dispenser, as shown.

BENJAMIN M. OSWELL.
